UNITED STATES PATENT OFFICE.

WILLIAM C. HINE, OF CLEVELAND, OHIO.

DESIGN FOR A PRESSED-METAL WHEEL.

59,351.

Specification for Design.

Patented Oct. 11, 1921.

Application filed March 22, 1919. Serial No. 284,506. Term of patent 7 years.

To all whom it may concern:

Be it known that I, WILLIAM C. HINE, a citizen of the United States, residing at Cleveland, in the county of Cuyahoga and State of Ohio, have invented a new, original, and ornamental Design for a Pressed-Metal Wheel, of which the following is a specification, reference being had to the accompanying drawings, forming a part thereof.

In said drawing, Figure 1 is a rear elevation, Fig. 2 a central section, and Fig. 3 a front elevation of a pressed metal wheel embodying my new design.

I claim:

The design for a pressed metal wheel, substantially as shown.

WILLIAM C. HINE.
